UNITED STATES PATENT OFFICE.

PHILLIP JACOB DREHER, OF TOLEDO, OHIO.

PLATEN-ROLL-TURNING MEANS FOR TYPE-WRITERS.

1,070,237.

Specification of Letters Patent.

Patented Aug. 12, 1913.

Original application filed August 29, 1911, Serial No. 646,661. Divided and this application filed February 16, 1912. Serial No. 677,934.

To all whom it may concern:

Be it known that I, PHILLIP JACOB DREHER, a citizen of the United States, and a resident of Toledo, in the county of Lucas and State of Ohio, have invented a certain new and useful Platen-Roll-Turning Means for Type-Writers; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to automatically operated typewriters, and has for its object the provision of means which is automatically operable at predetermined intervals to impart a rapid turning or sheet-feeding movement to the platen-roll of a typewriter, and is independent of the means customarily employed for turning the platen-roll to impart line spacing movements thereto.

The invention is fully described in the following specification, and while, in its broader aspect, it is capable of embodiment in numerous forms, a preferred embodiment thereof is illustrated in the accompanying drawings, in which,—

Figure 1 is a side elevation of the mechanism embodying my invention in association with a typewriter. Figs. 2, 3 and 4 are details of parts of such mechanism, and Fig. 5 is a partial central longitudinal section of an air bellows.

This application is a division of the application filed by me on August 29, 1911, Serial No. 646,661.

Referring to the drawings, 1 designates a typewriter desk or other suitable part with which my invention may be associated, 2 the lowered top portion thereof, and 3 a typewriter of any suitable form which rests upon the part 2. The typewriter 3 is provided with the customary typewriter carriage 4, which operates over the top portion of the machine in the usual or any suitable manner, and carries the customary platen-roll of which 5 is the shaft.

6 designates the frame of a sheet-feeding mechanism which is attached to the typewriter carriage 4 for movements therewith.

To accomplish a rapid intermittent turning of the platen-roll, for which my present

invention is adapted, I provide a ratchet-wheel 7 on one end of the platen-roll shaft 5, with which wheel a pawl 8, that is carried above the ratchet wheel by a push-bar 9, coacts. The bar 9 is mounted in bearings 10 attached to the associated end of the frame 6, and is normally held at the limit of its rearward movement by the action thereon of a coiled compression spring 11. The rearward movement of the bar 9 is limited by a stop 12 thereon coacting with one of the guides 10, and upon a forward movement of the bar 9 from its normal position the pawl 8 coacts with the ratchet wheel 7 to impart a predetermined rotary movement thereto.

A rapid reciprocation of the push-bar 9 is effected by the rotation of a wiper-wheel 13, which is carried by a shaft 14 in position for its wiper flanges 15 to coact with the rear end of the push-bar 9 to impart forward movements thereto when said bar stands in register with such flanges. The shaft 14 is mounted in a bearing bracket 16, which is secured to one side of the desk or case 1. This wiper-wheel is axially shiftable on its shaft to cause a clutch surface 17 on one end thereof to be moved into engagement with a clutch lug 18 on a pulley or other rotatable member 19, which pulley is mounted on the shaft 14 and is continuously driven during the operation of the machine from a motor 20 through the medium of a belt 21. A coiled compression spring 22 is interposed between the adjacent sides of the wheel 13 and pulley 19 to normally maintain the same in disengaged position. When the wiper-wheel is in normal or disengaged position its rotation is stopped by the engagement of one of the flanges 15 thereof with a stop lug 23 on the bracket 16, as best shown in Fig. 2.

The means employed for automatically moving the wiper-wheel into clutch engagement with the rotating member 19 at predetermined intervals during an operation of the machine, comprises, in the present instance, a shift lever 24 which is pivoted to a bracket 25, projecting from the adjacent casing side, with its upper end in forked engagement with a peripherally grooved hub portion of said wheel and its lower end attached to the movable part 26 of a bellows 27, whereby a collapsing of said bellows will impart a pulley engaging movement to the wheel 13.

It will be understood that the bellows 27, which is shown in conventional form, has a part in communication through a pipe 28 with a suction means 29 of any suitable form and a part in communication through a tube 30 with a passage of a tracker board 31. The term "bellows" as herein used means not only the bellows proper but also the internal or associated valve mechanism which normally closes communication between the suction means and the interior of the collapsible portion of the bellows, and is also automatically operated to open such communication when the associated tracker passage is open to permit the air suction to collapse the collapsible bellows parts, as well understood in the art. A belt 33 is shown, in the present instance, as leading from the motor 20 to the suction means 29 to operate the same.

Numerous forms of bellows 27 are on the market, and it will be sufficient for an understanding of the operation of the invention to describe one form only thereof, which is shown in detail in Fig. 5. In these bellows, 34 designates the body or stationary part and 35 the interior of the bellows proper. The body 34 is provided with a chamber 36, which has communication through the passage 37 with the suction pipe 28 and has communication through a passage 38 with the interior 35 of the bellows. A diaphragm 39 is disposed in the chamber 36 and divides it into two compartments, one of which has communication with both passages 37 and 38, while the other has communication through a passage 40 with the tube 30 leading from the associated tracker board passage. A disk-valve 41 is disposed in the passage 38, and has its stem projected into the chamber 36 and attached to the diaphragm 39. When the valve is raised by the suction action thereon from within the chamber 36 it closes the communication between such chamber and the passage 38 and when lowered, due to atmospheric pressure in the passage 40 upon the diaphragm 39, it is lowered and opens the communication between the chamber 36 and passage 38 to the bellows and closes the opening 42 from the passage 38 to the atmosphere. It is thus apparent that when the tracker passage is closed the suction action within the chamber 36 will move the valve 41 to close the communication between the suction means and the interior of the bellows and open the communication between the atmosphere and the bellows, and that upon an opening of the tracker passage the atmospheric pressure, which then rushes into the passage 40, acts upon the diaphragm 39 and effects a movement of the valve 41 to open communication between the suction means and the interior of the bellows so that a sudden collapsing of the bellows is effected. A

small bleed-opening 43 is provided between the passage 40 and the suction chamber 36 so that any air remaining in the passage 40 after the closing of the associated tracker passage will be slowly drawn therefrom to relieve the pressure on the side of the diaphragm 39 opposed to the valve.

The operation of my invention is as follows: Upon the feeding of a sheet into position to be engaged and fed by a rotation of the platen-roll, which initial feeding movement may be communicated to the sheet in any suitable manner, as by the mechanism described in my said former application Serial No. 646,661, a perforation in the control sheet 32 moves into register with the tracker-board passage in communication with the bellows 27 and permits the suction means 29 to act to effect a collapsing of the bellows and a consequent movement of the lever 24 to shift the wiper-wheel 13 into engagement with the drive pulley 19. Upon a rotation of the wheel 13 its fins or flanges 15 successively strike the push-bar 9 and impart rapid and successive sheet feeding movements to the platen-roll for the purpose of quickly moving the sheet into initial writing position. It will be understood that the length of feeding of the sheet in this manner is gaged by the length of the perforation in register with the associated tracker-board passage and that as soon as said perforation moves out of register with the tracker-board passage the spring 22 will act to force the wheel 13 to normally disengaged position and move the lever 24 to open the bellows. This same action is repeated when the writing of the letter or other matter has been completed so as to effect a rapid feeding-out movement of the sheet preparatory to the feeding of another sheet to the platen-roll, or such operation may occur at any point in the printing of the sheet as it may be desired to leave a considerable space in the body of the printed matter.

It is evident that a separate line spacing mechanism, for instance such as that described in my accompanying application Serial No. 641,560, filed July 31, 1911, may be used in connection with the typewriter for imparting the successive line spacing movements to the platen-roll and that my present mechanism does not interfere with nor does it coöperate with the regular line spacing mechanism to impart rotation to the roll. It is also evident that the use of a platen-roll turning mechanism of this character in connection with an automatically operated typewriter materially enhances the speed of working thereof, as the sheets are quickly fed to printing position and when the printing has been accomplished are then quickly fed from engagement with the platen-roll, thus enhancing the practicability of the invention.

ity and commercial value of apparatus of this class.

I wish it understood that my invention is not limited to any specific construction or arrangement of the parts except in so far as such limitations are specified in the claims.

Having thus described my invention, what I claim as new and desire to secure by Letters Patent, is,

- 10 1. The combination with the platen roll of a typewriter, of a reciprocally movable member having pawl and ratchet connection with the platen roll, and mechanism having a pneumatically controlled rotatable part 15 operable to impart reciprocal movements to said member.
- 20 2. The combination with the platen roll of a typewriter, of a reciprocally movable member having pawl and ratchet connection with the platen roll and yieldingly retained 25 in one position of its movement, and mechanism having a rotatable part which is operable to impart reciprocal movements in one direction to said member.
- 30 3. The combination with the platen roll of a typewriter, of pawl and ratchet means operable to impart intermittent rotation to the platen roll, a rotatable member for acting on said pawl to impart roll turning movements to said ratchet, driving means normally disengaged from said member and mechanism automatically operable to engage 35 said member and driving means.
- 35 4. The combination with the platen roll of a typewriter, of pawl and ratchet means for imparting intermittent rotary movements to the platen roll, reciprocatory means for

moving the pawl, a spring for moving said reciprocatory means in one direction, a rotary wiper member for imparting movements to said reciprocatory means in opposition to said spring, means for driving said wiper member, and mechanism pneumatically operable to shift said member into driving engagement with said driving 45 means.

5. The combination with the platen roll of a typewriter, of pawl and ratchet means for imparting intermittent rotary movements to said roll, a shiftable wiper wheel adapted 50 when rotating to impart ratchet turning movements to the pawl, means for driving said wheel, and pneumatically controlled mechanism for moving the wheel into and out of driving engagement with said driv- 55 ing means at predetermined intervals.

6. The combination with the platen-roll of a typewriter, of a pawl and ratchet operable to turn said roll, a push-bar yieldingly movable in one direction and attached to 60 said pawl for imparting ratchet turning movements thereto, a rotatable member operable to impart successive reciprocatory movements to said push-bar, and a motor for driving and pneumatic means for controlling said member.

In testimony whereof, I have hereunto signed my name to this specification in the presence of two subscribing witnesses.

PHILLIP JACOB DREHER.
